UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

CONVEYER FOR METAL BARS.

No. 849,122.

Specification of Letters Patent.

Patented April 2, 1907.

Application filed September 19, 1905. Serial No. 279,136.

To all whom it may concern:

Be it known that I, JEROME R. GEORGE, a citizen of the United States, residing at Worcester, in the county of Worcester and 5 Commonwealth of Massachusetts, have invented a new and useful Improvement in Conveyers for Metal Bars, of which the following is a specification accompanied by drawings, forming a part of the same, in 10 which—

Figure 1 represents a plan view of a conveyer embodying my invention. Fig. 2 is a side elevation. Figs. 3 and 4 show modified forms of feeding metal bars to the conveying 15 mechanism, and Fig. 5 shows a form of construction of my improved conveyer by which metal bars may be transferred from one elevation to another, and Figs. 6, 7, and 8 represent a top and two end views showing means 20 for decreasing the longitudinal speed of a bar on the conical conveyer-rolls.

Similar reference letters and figures refer to similar parts in the different views.

My invention relates to a conveying mechanism for transferring metal bars from one position to another, either in the same plane or in different planes; and it consists in the employment of rotating screw-threaded conveyer-shafts upon which the bars are supported, with means for feeding the bars upon the screw-threaded shafts.

It further consists in providing means for limiting the endwise movement of the bars and in certain novel features of construction 35 and arrangement of parts, as hereinafter described, and pointed out in the annexed claims.

Referring to Figs. 1 and 2 of the drawings, 1, 2, and 3 denote screw-threaded conveyer-shafts, each of which is provided with a worm-gear 4, engaging worms 5 on a shaft 6, whereby a slow rotary motion is imparted to the screw-threaded conveyer-shafts 1, 2, and 3. The spaces between the screw-threaded 45 conveyer-shafts 1, 2, and 3 are reduced at one end of the conveying mechanism by the insertion of the short screw-threaded shafts 7 and 8, which are likewise rotated from the shaft 6. All the screw-threaded conveyer-shafts 50 are journaled at one end in suitable bearings in a framework 9. The shorter shafts 7 and 8 are journaled at their opposite ends in bearings 10 and 11. Each of the

longer shafts 1, 2, and 3 have their opposite ends supported upon a pair of friction-rolls 55 12. Between the ends of the screw-threads I place a series of conveyer-rolls 13, having their upper surfaces lying in a plane slightly above the tops of the screw-threaded conveyer-shafts, so that a bar 14 as it rests upon 60 the top of the conveyer-rolls 13 may be pushed by reciprocating pushers 15 from the conveyer-rolls upon the screw-threaded shafts. The reciprocating pushers 15 are operatively connected by links 16 with any 65 suitable actuating mechanism (not shown) whereby they may be moved back and forth in their bearings to transfer metal bars from the conveyer-rolls 13 to the screw-threaded conveyer-shafts. The conveyer-rolls 13 have 70 a geared connection with the driving-shaft 17, by which they are rotated in the proper direction to move the metal bar 14 longitudinally in the direction of the arrow 18. At one side of the conveying mechanism I place 75 a stop-plate 19, by which the longitudinal movement of the bar 14 is checked. As the bars are transferred upon the rotating screw-threaded conveyer-shafts a sidewise movement will be imparted to the bars in the direction of the arrows 20 until the bars have 80 reached the opposite ends of the conveyer-shafts, where they will be delivered upon a series of conveyer-rolls 21, having a geared connection with a driving-shaft 22, by which 85 the bars are moved longitudinally and delivered from my improved conveying mechanism.

At the beginning of the conveying process when the metal bars are heated and therefore more ductile I support the bars at frequent intervals by the insertion of the short conveyer-shafts 7 and 8; but as the bars are cooled during their process across the conveyer they become sufficiently stiffened to support their weight across the wider spaces between the longer conveyer-shafts 1, 2, and 3.

The action of the screw-threaded conveyer-shafts not only moves the metal bars with a 100 slow sidewise movement from one end of the conveyer to the other, but they also tend to impart a longitudinal movement to the metal bars to carry them against and hold them in contact with a stop-plate 19. In 105 order that this tendency to longitudinal

movement of the bars on the screw-threaded shafts may not be unduly great, I prefer to construct a portion of the screw-threaded conveyer-shafts with reverse screw-threads, as illustrated in Fig. 1, in which shafts 2, 3, and 7 are provided with left-hand screw-threads, which when the shafts are rotated to the right will move the metal bars toward the opposite ends of the shafts and also toward the stop-plate 19, while the screw-threaded shafts 1 and 8 have right-hand screw-threads, which counteract the tendency to longitudinal movement of the bars.

In Figs. 1 and 2 the bars are fed longitudinally to the conveyer upon the rotating cylindrical conveyer-rolls 13; but in Figs. 3 and 4 the feeding conveyer-rolls are represented as conical, with the delivery end of the roll the smallest, so that the longitudinal movement of the bar is decreased in speed as the bar is moved sidewise toward the delivery end of the roll.

In Fig. 4 the conical conveyer-roll 23 has its upper supporting-surface 24 arranged in a horizontal plane, so that a metal bar 25 may be supported thereon without any tendency to sidewise movement until it is pushed from the conveyer-roll 23 to the screw-threaded shaft 26 by a reciprocating pusher 27.

In Fig. 3 the conical conveyer-roll 28 is represented with its upper or supporting surface 29 inclined sufficiently to cause a metal bar 30 to be moved by gravity off the conveyer-roll 28 upon the screw-threaded conveyer-shaft 31. During the longitudinal movement of the bar 30 upon the conveyer-roll 28 it is held from sidewise movement by gravity by means of a radial arm 32 on a hub 33, which is held in proper position by hand or otherwise to prevent the sidewise movement of the bar 30 until the proper time arrives for the delivery of the bar 30 upon the screw-threaded conveyer-shaft 31, when the hub 33 is rotated in the direction of the arrow 34 to remove the retaining radial arm 32 and bring the next radial arm 35 in proper position to retain the succeeding metal bar.

In Figs. 1 and 2 the axes of the screw-threaded conveyer-shafts are arranged in a horizontal plane, and the metal bars 36 resting thereon lie in the angle formed by the screw-threads and are transferred by the spiral action of the screw-threads from one end of the conveyer-shafts to the other.

In Fig. 5 I have shown a modification which consists in arranging the axes of the screw-threaded conveyer-shafts 36^a at an oblique angle to a horizontal plane and changing the form of the screw-threads 37 to provide supporting sides 38, adapted to hold the metal bars 39 against gravity as they are being moved toward the upper end of the screw-threaded conveyer-shaft. The inclined conveyer-shaft 36^a is journaled at

one end in a framework 40 and rotated by a geared connection with a shaft 41, with its free end supported upon a pair of friction-rolls 42 in the same manner as the horizontal shafts 1, 2, and 3 are supported. The bars are fed to the conveyer by a longitudinal movement upon rotating conveyer-rolls 43, from which they are pushed upon the screw-threaded conveyer-shafts 36^a, from which they are delivered to rotating conveyer-rolls 44. With a screw-threaded conveyer-shaft like that shown at 36^a, having screw-threads 37, it will be obvious that metal bars when once loaded upon the screw-threads 37 can be moved upwardly by the rotation of the shafts in one direction or downwardly by the rotation of the shafts in the opposite direction, allowing the metal bars to be lowered from a lower to a higher plane, or vice versa. When the metal bars are supported upon a series of screw-threaded conveyer-shafts, each bar rests by gravity against two sides of adjacent screw-threads, and as the sides of the several screw-threads supporting the bar lie in the same plane the weight of the bar when in a heated and ductile condition tends to bring the bar into alignment with the sides of the screw-thread, and therefore straighten it.

Fig. 6 represents a top view, and Fig. 7 an end view, of one end of my improved conveyer, in which the conical conveyer-rolls 45 are placed, as in Fig. 3, with their upper or supporting surfaces 46 inclined to cause a metal bar to be moved by gravity off the conveyer-rolls 45 upon the screw-threaded conveyer-shafts 47, with the stop-plate 19 in position to limit the longitudinal movement of a metal bar. In Figs. 6 and 7, however, I have shown means for gradually decreasing the speed of the metal bar as it approaches the stop-plate, consisting of a rocking shaft 48, journaled above the conical conveyer-rolls 45 and having a radial blade 49 extending downward in proximity to the supporting-surface 46 of the conveyer-rolls and serving as a stop for the metal bar to prevent it from being moved by gravity off the inclined surface of the rolls. The rocking shaft 48 is rocked by any suitable means—in the present instance by means of a lever-handle 50, which is raised or lowered to change the position of the blade 49. As the metal bar 51 enters upon the conical conveyer-roll the handle 50 is raised to bring the blade 49 in position to hold the bar near the larger ends of the conical rolls, where the surface speed of the roll is the greatest. As the metal approaches the stop-plate 19 the handle 50 is lowered, moving the radial blade toward the smaller end of the conical rolls, when the surface speed of the roll is lessened, thereby reducing the speed of the metal bar as it comes into contact with the stop-plate. A further depression of the handle 50 allows the metal bar to

pass off the conical rolls upon the screw-threaded conveyer-shafts 47 when the handle 50 is raised to restore the blade 49 to its original position to receive the succeeding metal bar. In Fig. 8 the same result is accomplished by a revolving shaft 52, having a series of radial blades 53 suitably spaced, whereby as a metal bar is being delivered from the rolls past one of the blades the succeeding bar will be retained by the next succeeding blade, allowing the shaft 52 to be intermittently rotated in the same direction.

What I claim as my invention, and desire to secure by Letters Patent, is—

1. A conveyer for metal bars, consisting of a series of screw-threaded rotating shafts, and a series of independently-rotating conveyer-rolls arranged to support a metal bar opposite the ends of said screw-threaded shafts.

2. A conveyer for metal bars, consisting of a series of screw-threaded rotating shafts, and a series of independently-driven conveyer-rolls arranged to support a metal bar opposite the ends of said screw-threaded shafts and in a plane above the upper or supporting surfaces of said shafts.

3. A conveyer for metal bars, consisting of a series of screw-threaded shafts, a series of independently-driven conveyer-rolls arranged to support a metal bar opposite the ends of said screw-threaded shafts, and means for transferring a metal bar from said conveyer-rolls to said screw-threaded shafts.

4. In a conveyer for metal bars, the combination with a series of rotating screw-threaded shafts, of rotating rolls interposed between said shafts.

5. In a conveyer for metal bars, the combination of a series of screw-threaded rotating bars, and means for feeding a metal bar upon said shafts by a sidewise movement of the bar over the ends of the shafts.

6. In a conveyer for metal bars, the combination of a series of rotating shafts having screw-threaded sections, conical rotating rolls, and means for delivering a metal bar from said rolls to the screw-threaded sections of said shafts.

7. In a conveyer for metal bars, the combination of a series of rotating screw-threaded

shafts lying in the same plane, with the delivery ends of said shafts the highest, and with the shape of said screw-threads adapted to hold a metal bar against gravity acting in a direction at an oblique angle to the axes of said shafts, and means for feeding a metal bar transversely to said shafts and into contact with the screw-threads.

8. In a conveyer for metal bars, the combination of a series of parallel shafts lying in the same plane, a portion of said shafts having a right-hand and a portion left-hand screw-threads.

9. In a conveyer for metal bars, the combination of a series of screw-threaded shafts having parallel axes lying in the same plane and adapted to hold a metal bar lying transversely thereon, means for feeding a bar upon the receiving ends of said shafts, and shorter screw-threaded shafts interposed between the receiving ends of the longer shafts.

10. In a conveyer for metal bars, the combination of a screw-threaded shaft journaled at one end in a bearing, and a pair of rolls arranged to support the opposite end of said shaft.

11. In a conveyer for metal bars, the combination of a series of screw-threaded shafts, means for simultaneously rotating said shafts, a series of conical conveyer-rolls having their supporting-surfaces inclined to allow a metal bar to pass by gravity upon said screw-threaded shafts, of means for varying the position of a metal bar on said conical rolls, whereby the longitudinal movement of the metal bar is varied in speed.

12. In a conveyer for metal bars, the combination of a series of rotating conical conveyer-rolls for imparting a longitudinal movement to a metal bar, having their supporting-surfaces inclined, a stop-plate for limiting the longitudinal movement of the bar, a movable plate for retaining the bar on said rolls against gravity, and means for changing the position of said retaining-plate.

Dated this 18th day of September, 1905.
